UNITED STATES PATENT OFFICE.

THOMAS LEOPOLD WILLSON AND MAXIMILLIAN MATTHEUS HAFF, OF OTTAWA,
ONTARIO, CANADA; SAID HAFF ASSIGNOR TO SAID WILLSON.

METHOD OF OBTAINING NITROGEN AND MAKING COMPOUNDS THEREFROM.

1,084,774.

Specification of Letters Patent.

Patented Jan. 20, 1914.

Application filed April 9, 1910, Serial No. 554,376. Renewed November 29, 1913. Serial No. 803,858.

To all whom it may concern:

Be it known that we, THOMAS LEOPOLD WILLSON and MAXIMILLIAN MATTHEUS HAFF, both of the city of Ottawa, Province of Ontario, Canada, subjects of the King of Great Britain, have invented certain new and useful Improvements in Methods of Obtaining Nitrogen and Making Compounds Therefrom, of which the following is a specification.

Our invention relates to an improved method of obtaining nitrogen and the objects of our invention are to manufacture the nitrogen in such a way that the by-product produced will be useful in an industry which may be readily allied with that of manufacturing the nitrogen compounds, and further to obtain the nitrogen as economically and in as pure a form as possible.

20 The drawing illustrates a sectional elevation of an apparatus which may be used to carry out the process.

According to the present invention, the nitrogen is obtained by first burning sulfur or a sulfid ore in a confined body of air and the sulfur compound, in the preferred mode of carrying out the process, is utilized to make the bisulfite liquor used in paper manufacture. The resultant gas from this step is practically air rich in nitrogen, and to remove the remaining small percentage of oxygen it is proposed to pass the air enriched in nitrogen again over heated sulfur or sulfid ore and in order to maintain either of these in a state of combustion it is necessary to apply external heat to consume the small percentage of oxygen in the gaseous mixture. The nitrogen resulting from the process is then directly converted into a form of commercial nitrogen compound such as cyanamid or nitrids. As far as the first part of the process is concerned it is immaterial how the sulfur compound is extracted and utilized. It might under certain conditions be used to form sulfuric acid in the well known manner, but the formation of the sulfite liquor as above described will be found extremely convenient as in practice a paper factory may readily be allied with a factory for producing nitrogen compounds.

The first part of the process is identical with that carried out ordinarily to produce bisulfite liquor. According to this process a confined body of air is passed over burning sulfur and then either led through a

tower containing calcium oxide and magnesium oxide or passed through a mixture of lime and water, the reactions for this process being as follows:

The first part of the process may be modified if desired by substituting a sulfid ore for the sulfur, the substitution having the advantage that the extraction of oxygen is likely to be more complete. With an iron sulfid ore, such as iron pyrites, the first reaction would be:

To maintain the ore in a state of combustion it will probably be necessary to apply external heat and this may be done in any well known manner, or in any suitable type of furnace. Otherwise the heat might be applied to the air or gaseous mixture in a suitable regenerative gas heater. This modification has the further advantage that the ore is oxidized and so brought to a condition in which the metal may be readily extracted. It will thus be apparent that this step of the process, which possesses novelty in itself, might be operated alone to form a convenient source for the simultaneous production of nitrogen and sulfur compounds and the oxidization of the pyrites ore.

In using the process in connection with paper manufacture previously, the only product which has been recovered has been the bisulfite of calcium ($CaO(SO_3)_2 \cdot xH_2O$), the gaseous mixture of nitrogen with a small percentage of unacted on air, (probably five to twenty-five per cent.) being allowed to escape. According to the present invention this resultant gaseous mixture, which may be termed "air enriched in nitrogen" is passed over a further quantity of heated sulfur, and to maintain the second supply of sulfur or sulfur compound in a state of combustion it is necessary to apply external heat which may be done in any suitable furnace designed for the purpose. The heat will cause the sulfur to combine with any residual oxygen in the mixture, to form sulfur dioxide as before, which may be separated by passing through a lime tower or lime

water as previously, finally leaving nitrogen in an extremely pure state. This nitrogen is then directly utilized to produce nitrogen compounds in any way at present known in the art. For example it may be employed in the process set forth in the United States Patent #741,396 granted October 13th 1903 to the William Laboratory Co., as assignee of C. de Chalmot, in which patent nitrogen is passed through a heated mass of reduced metal, metalloid salt or oxid. Otherwise it may be employed to produce cyanamid by passing nitrogen through a mass of calcium carbid heated to a red heat.

Referring to the apparatus which we have illustrated for carrying out the process hereinbefore described, A represents a sulfur burner of any usual type, being of muffle construction having trays 10 for the sulfur and a stirring rabble 11 by which the sulfurous material may be maintained in a burning state. The air enriched in nitrogen being led in through the conduit 12, is drawn through the burner into a conduit 13 by a suitable blower B, the gas being forced by the blower through a suitable scrubber C, thence below the surface of an aqueous solution in a tank E, thence it is drawn by a second blower F and forced beneath the surface of a second aqueous solution in a tank G both of said aqueous solutions being adapted to wash out the sulfur oxid. From the tank G the nitrogen gas may be drawn and forced to any desired place of consumption by suitable means such as blower H.

It may be mentioned that the step of the process specified in the claims as "burning sulfur in a confined body of air" is intended to include both the case where the sulfur is burned alone and the case where a sulfur ore is burned.

As many changes could be made in the above process and many apparently widely different embodiments of our invention, with 45 in the scope of the claims, could be made

without departing from the spirit or scope thereof, it is intended that all matter contained in the accompanying specification shall be interpreted as illustrative and not in a limiting sense.

50

What we claim is:

1. The process of obtaining nitrogen from the atmosphere which consists in burning sulfur in a confined body of air and passing the resultant gaseous mixture through a solution containing lime to form a bisulfite liquor and then passing the resultant gas over sulfurous de-oxidizing means.

55

2. The process of obtaining nitrogen from the atmosphere which consists in burning sulfur in a confined body of air and passing the resultant gaseous mixture through a solution containing lime to form bisulfite liquor and then passing the resultant mixture over externally heated sulfur and then separating the nitrogen gas.

60

3. The process of obtaining nitrogen from the atmosphere, which consists in passing air enriched in nitrogen over an externally heated substance which normally may be burned in the air, and removing the oxygen compound.

65

4. The process of obtaining nitrogen from the atmosphere which consists in passing air enriched in nitrogen over externally heated sulfur, removing the oxysulfur compound and then recovering the nitrogen.

75

5. The process of obtaining nitrogen from the atmosphere which consists in passing heated air enriched in nitrogen over sulfur and removing the oxysulfur compound formed.

80

In witness whereof we have hereunto set our hands in the presence of two witnesses.

THOMAS LEOPOLD WILLSON.
MAXIMILLIAN MATTHEUS HAFF.
